SYNCHRONIZATION OF DEFLECTING CIRCUITS

Gordon L. Fredendall, Westmont, and Alfred C. Schroeder, Camden, N. J., assignors to Radio Corporation of America, a corporation of Delaware

Application December 31, 1941, Serial No. 425,198

8 Claims. (Cl. 178—7.5)

Our invention relates to automatic frequency control or phase control circuits and particularly to the synchronization of cathode ray deflecting circuits in television receivers or the like.

The deflecting circuits of a television receiver usually contain an oscillator which is to be synchronized by incoming synchronizing pulses whereby the scanning at the receiver is held in synchronism with that at the transmitter. It has previously been proposed that this synchronization be obtained by employing an automatic frequency control circuit responsive to any change in the time relation of the synchronizing pulses and the saw-tooth waves produced by the deflecting circuit.

An object of the present invention is to provide an improved synchronizing circuit of the above-described type.

A further object of the invention is to provide an improved method of and means for synchronizing a cathode ray deflecting circuit.

A further object of the invention is to provide an improved television synchronizing circuit that is not greatly affected by noise in the incoming signal.

A still further object of the invention is to provide an improved television receiver.

In a preferred embodiment of the invention, the automatic frequency control voltage is obtained by employing a pair of peak rectifiers connected in balanced relation which have a mixture of synchronizing pulses and saw-tooth deflection waves applied thereto. The said pulses and saw-tooth waves are so mixed that the saw-tooth waves have the same polarity at the two rectifiers while the pulses are of opposite polarity. As a result, when the synchronizing pulses are located on the steep side of the saw-tooth waves, a change in the phase relation of the pulses and saw-tooth waves will cause the peak amplitude of one mixed signal to increase and cause the peak amplitude of the other mixed signal to decrease. The resulting change in the peak rectifier outputs is utilized to control the frequency of the deflecting circuit oscillator.

The invention will be better understood from the following description taken in connection with the accompanying drawings in which

Figure 1 is a circuit diagram of one embodiment

of our invention as applied to a television receiver.

Figure 2 is a circuit diagram showing a modification of the peak rectifier circuit of Figure 1, and

Figures 3a to 3e and 4a to 4f are curves that are referred to in explaining the invention.

Like parts in the several figures are indicated by the same reference characters.

10 In Figure 1, a video amplifier tube and a cathode ray tube are shown at 10 and 11, respectively, the tube 10 being biased by the usual cathode resistor 12 and bypass condenser 13. The tubes 10 and 11 are resistance-capacity coupled by means of the video amplifier's plate resistor 14 and peaking coil 16, a coupling condenser 17 and a grid leak resistor 18.

The control grid circuit of the cathode ray tube 11 is completed through the cathode resistor 19 of a vacuum tube 21 which functions both as a direct current or background inserter for the cathode ray tube and as a separating tube for passing synchronizing pulses only to the synchronizing or automatic frequency control circuits of the saw-tooth wave deflecting circuits as explained below.

20 The horizontal deflecting coils indicated at 22 and the vertical deflecting coils indicated at 23 are supplied with saw-tooth current from a horizontal deflecting circuit 24 and from a vertical deflecting circuit 24a, respectively. These deflecting circuits may be of any suitable design. In the example illustrated, the deflecting circuit 24 includes a blocking oscillator which comprises a vacuum tube 27, a feedback transformer 28, a grid condenser 29 and a grid leak resistor 31. The blocking oscillator pulses are applied to a discharge tube 32 of a conventional saw-tooth wave generating circuit which includes condensers 33 and 34 that are charged through the plate resistor 36.

30 The saw-tooth voltage appearing across condensers 33 and 34 in series is applied to a high impedance output tube 37 which has its plate circuit coupled to deflecting coils 22 through the coupling condenser 38 and the choke coil 39.

35 The saw-tooth voltage across condenser 38 is also supplied by way of a conductor 41 to the AFC circuit 42 for the horizontal deflecting circuit 24.

The AFC circuit 42 comprises a transformer 43 having a primary 44 and a secondary 45. A resistor 47 across the secondary 45 is connected at its midpoint to the conductor 41.

One end of secondary 45 is coupled through a condenser 48 to the cathode of a diode 51; the other end is coupled through a condenser 52 to the plate of a diode 53.

The diodes 51 and 53 are made to function as peak rectifiers by giving the discharge paths of condensers 48 and 52 a long time constant. The discharge path of condenser 48 is through a resistor 54 connected across diode 51 and through a biasing battery or other suitable biasing source 56. The discharge path for condenser 52 is through a resistor 57 connected between the plate of diode 53 and ground.

The plate and the cathode of diodes 51 and 53, respectively, are held slightly negative with respect to ground by the biasing source 56 as indicated.

The cathode of diode 51 and the plate of diode 53, each of which varies in D.-C. potential in accordance with the peak rectification, are connected to opposite ends of a mid-tapped potentiometer comprising resistors 58 and 59, the said mid-tap being D.-C. connected to the grid of an amplifier tube 61.

As previously indicated, saw-tooth voltage is fed into the AFC circuit 42 at the midpoint of resistor 47. The horizontal synchronizing pulses are fed into this circuit through the transformer 43, the transformer having a sufficiently poor frequency response to prevent the transfer of the comparatively low frequency vertical synchronizing pulses. Also, the transformer preferably narrows the horizontal synchronizing pulse by differentiating them.

The tube 21 operates to remove the picture signal and pass only the synchronizing pulses since its grid and cathode elements act as a diode to rectify the peaks of synchronizing pulses which are applied to said cathode with negative polarity, the grid being grounded. The signal is applied from the plate resistor 14 to the cathode of tube 21 through a resistor 40 and a condenser 50 whereby the rectified current charges condenser 50 to a value which varies with the peak amplitude of the synchronizing pulses. The resistor 40 isolates condenser 50 from the plate circuit of the video amplifier 10 whereby its frequency-response is not impaired. It will be understood that the discharge circuit for condenser 50 has a time constant such that most of the condenser charge holds over between successive horizontal synchronizing pulses as in other forms of D.-C. inserting circuits.

The separated synchronizing pulses are amplified by the tube 21 and applied to a D.-C. amplifier 60 which includes in its plate circuit the transformer 43 for passing horizontal synchronizing pulses only and a transformer 45 having its primary and secondary shunted by condensers 3 and 9, respectively, for passing the vertical synchronizing pulses only.

For a certain assumed phase relation of sawtooth voltages and synchronizing pulses, the voltages appearing at the points B and C of the resistor 47 are shown in Figs. 3a and 3b, respectively. The sawtooth voltages eca at these points are of the same polarity while the voltage pulses eab and eac are of opposite polarity. Any change in the phase relation of the sawtooth waves and the synchronizing pulses will cause an increase in the peak amplitude of one composite signal and

a decrease in the peak amplitude of the other. This is shown in Figs. 4a and 4b (where the direct current component is shown included in the signals). To simplify the drawings, the voltage pulses eca and ecb are not shown as differentiated pulses, only the portion of the pulse that is effective being shown.

At the points D and E, i. e. at the cathode and the plate of diodes 53 and 51, respectively, the voltages are those shown in Figs. 3c and 3d, respectively. These voltages include the D.-C. voltage inserted by the peak rectifier action of the diodes 53 and 51. More specifically, it will be noted that the peaks of the synchronizing pulses are held at the reference level of -1.5 volts in the particular example assumed.

The signal appearing at the midpoint F of the resistors 58 and 59 is shown in Fig. 3e. It will be seen that the synchronizing pulses have been balanced out, leaving a signal containing only the D.-C. and sawtooth wave components. This signal is amplified by the amplifier tube 61 which has in its plate circuit the usual plate resistor 52 and, in addition, a filter condenser 63 and an auxiliary filtering means comprising a resistor 64 and a comparatively large capacity condenser 66. Thus, the sawtooth component of the signal shown in Fig. 3e is filtered out and a D.-C. control potential is applied through a conductor 67 to the grid of the blocking oscillator tube 27 for controlling the blocking oscillator frequency. The auxiliary filtering means 64-66 is not necessary for satisfactory operation but it is helpful in noisy locations since it filters out random noise pulses.

It has been assumed that the deflecting circuit adjustment is such that it is held in synchronism under the condition illustrated in Figs. 3a to 3e. Assume now that the blocking oscillator starts to slow down so that the phase relation of the sawtooth waves and the synchronizing pulses changes to that shown in Figs. 4a and 4b, this particular phase relation, incidentally, being a limiting condition. As a result, the D.-C. component as measured from the reference voltage of -1.5 volts is increased at point D and decreased at point E as will be seen by comparing Figs. 3c and 4a and by comparing Figs. 3d and 4b. Or, considering the potentials with respect to ground, the point D has gone more negative and the point E has also gone more negative. The potential at the midpoint F will be intermediate these two potentials as shown at Fig. 4c and will be more negative than before (compare with Fig. 3e).

Since amplifier tube 61 reverses the polarity of a signal, the D.-C. control potential applied to the blocking oscillator is less negative and the oscillator is speeded up.

The opposite action is illustrated in Figs. 4d, 4e and 4f. Since these figures correspond to Figs. 4a, 4b and 4c they are self-explanatory. Comparing Figs. 4f and 3e, it will be seen that when the phase shift is in this direction the point F goes less negative with respect to ground whereby the blocking oscillator will be slowed down.

The foregoing description applies equally well to the vertical deflecting circuit shown at 42a. In the vertical deflecting circuit parts corresponding to those in the horizontal deflecting circuit are indicated by the same reference numerals followed by the letter "a." It may be noted that the vertical deflecting circuit preferably includes the well known "peaking" re-

sistor indicated at 75 which is in series with the sawtooth wave condensers and that it may also include a cathode resistor 76 for further improving the wave form of the deflecting current flowing through the vertical deflecting coils.

In Figure 2, there is shown a different output circuit for the peak rectifier diodes 51 and 53. The potentials at points E and D are applied to the grids of amplifier tubes 71 and 72 which have a common plate resistor 73 whereby the said potentials are added and applied to the filter condenser 63. The operation is similar to that previously described.

Values for various circuit elements in Figure 1 are given below merely by way of example:

Condenser 8	μfd	.005
Condenser 9	do	.01
Condenser 49	do	.001
Condenser 52	do	.001
Condenser 49a	do	.1
Condenser 52a	do	.1
Condenser 63	do	.1
Condenser 66	do	100
Condenser 63a	do	.1
Condenser 66a	do	100
Resistor 47	ohms	16,400
Resistor 47a	do	9,400
Resistor 54	megohms	4.7
Resistor 57	do	4.7
Resistor 54a	do	2.2
Resistor 57a	do	2.2
Resistor 58	ohms	100,000
Resistor 59	do	100,000
Resistor 58a	megohms	10
Resistor 59a	do	10
Resistor 64	ohms variable	10,000
Resistor 64a	do	10,000

We claim as our invention:

1. In the operation of an oscillator, the method of synchronizing said oscillator with synchronizing pulses which includes producing a pair of waves having a definite time relation with respect to the frequency of said oscillator and having simultaneously sloping portions which slope in the same direction, superimposing with opposite polarity said synchronizing pulses upon said sloped portions, respectively, to produce a pair of resultant pulses, producing a frequency control voltage having a value which changes in response to a change in the relative peak amplitudes of said resultant pulses, and applying said control voltage to said oscillator to control its frequency.

2. In combination, a pair of peak rectifiers having input circuits and output circuits, an oscillator and means for generating a periodically recurring wave occurring in a fixed time relation to the oscillator frequency, said wave having a sloping side, means for applying said wave to said rectifiers with like polarity at each rectifier, means for applying periodically recurring voltage pulses to said rectifiers with the polarity at one rectifier opposite that at the other rectifier and in additive relation to said wave, said rectifiers being connected in the direction to rectify the applied pulses, and means for combining the outputs of said output circuits and for utilizing the combined output as a frequency control voltage which is applied to said oscillator.

3. In a television receiver, a pair of peak rectifiers having input circuits and output circuits 75

each connected in balanced relation, a cathode ray deflecting circuit which includes an oscillator and which also includes means for generating a steep-sided wave occurring in a fixed time relation to the oscillator frequency, means for applying said wave to said rectifiers with like polarity at each rectifier, means for applying incoming synchronizing pulses to said rectifiers with the polarity at one rectifier opposite that at

10 the other rectifier and in additive relation to said wave whereby a frequency control voltage appears in said output circuit, and means for utilizing said frequency control voltage to control the frequency of said oscillator.

15 4. A deflecting circuit having an oscillator therein, means for producing a pair of voltage waves having a definite time relation with respect to the frequency of said oscillator and having simultaneously sloping portions which slope in the same direction, means for superimposing received synchronizing pulses of opposite polarity upon said sloped portions, respectively, to produce a pair of resultant pulses, means for producing a frequency control voltage having a value which changes in response to a change in the relative peak amplitudes of said resultant pulses, and means for controlling the frequency of said oscillator in accordance with said control voltage.

20 5. In a television receiver, a pair of peak rectifiers each having an input circuit and an output circuit, said input circuits being connected in balanced relation with respect to a source of synchronizing pulses, a cathode ray deflecting circuit which includes an oscillator and means for generating a steep-sided wave occurring in a fixed time relation to the oscillator frequency, means for applying said wave to said rectifiers with like polarity at each rectifier whereby it is added to 25 synchronizing pulses of one polarity at one of said rectifiers and is added to synchronizing pulses of the opposite polarity at the other of said rectifiers, and means for utilizing the output appearing in said output circuit as a frequency control voltage to hold said oscillator in synchronism with said pulses.

6. In a television receiver, a pair of peak rectifiers having input circuits and output circuits each connected in balanced relation, each of said rectifiers having an electrode which is brought to a certain direct current potential by the peak rectifier action, a cathode ray deflecting circuit which includes an oscillator and means for generating a steep-sided wave occurring in a fixed time relation to the oscillator frequency, means for applying said wave to said rectifiers with like polarity at each rectifier, means for applying incoming synchronizing pulses to said rectifiers with the polarity at one rectifier opposite that at the other rectifier and in additive relation to said wave, said balanced output circuit connection comprising resistor elements connected between said peak rectifier electrodes, means for charging a filter condenser in accordance with the potential appearing at an intermediate point on said resistor elements, and means for utilizing the voltage across said filter condenser to control the frequency of said oscillator.

7. The invention according to claim 6 wherein each of said peak rectifiers comprises a diode and wherein one of said electrodes is a diode cathode and the other of said electrodes is a diode plate.

8. In combination, an oscillator, a source of periodically recurring synchronizing pulses, means for producing periodically recurring waves

having a definite time relation with respect to the frequency of said oscillator and each having a sloping portion, a pair of rectifiers, means for applying said waves with like polarity to said rectifiers, means for superimposing with opposite polarity synchronizing pulses from said source upon said sloped portions of said waves at said rectifiers, respectively, to produce a pair of resultant pulses, means including said recti-

5 fiers for producing a frequency control voltage having a value which changes in response to a change in the relative peak amplitudes of said resultant pulses, and means for applying said control voltage to said oscillator to control its frequency.
